UNITED STATES PATENT OFFICE.

GRANDON D. GATES, OF DERBY, CONNECTICUT, ASSIGNOR TO THE CREAMERY PACK-
AGE MFG. COMPANY, OF CHICAGO, ILLINOIS, A CORPORATION OF ILLINOIS.

LIQUID-COOLING DEVICE.

Application filed September 29, 1926. Serial No. 138,367.

The invention relates to liquid cooling devices of the internal or double tube type, and more particularly to the heads forming the elbow connections between the tubes.

Such coolers comprise tiers of horizontal double spaced tubes, the ends of the inner and outer tubes respectively being connected for the flow of liquid successively through the tubes of the tier. The use of such coolers in the treatment of milk in dairy plants necessitates a construction permitting ready access to all surfaces in contact with the milk for cleaning and sterilization after use.

An object of the present invention is to provide an improved construction of the heads connecting the tube ends wherein simple arrangement, few parts, and adaptability to easy assembling and disassembling is attained. Another object is to provide means for preventing any leakage or bypassing of the liquid between the passages connecting the inner tubes and the passages connecting the outer tubes. Other objects will be apparent in the following description 25 of a preferred embodiment of the invention.

Referring to the drawings, Fig. 1 is a plan view of one of the heads, and Fig. 2 an end view of the same. Fig. 3 is a sectional elevation of the head and fractional parts of the tubes to which it is connected, and Fig. 4 is an end view of the head with the cover or cap removed. Fig. 5 is a sectional view of the leakage-preventing packing ring.

Referring to the drawings, the numeral 1 indicates the base element of the head construction, which is provided with a pair of rearwardly extending annular flanges 2 and 3, within which are secured a pair of outer tubes 4 and 5, the base 1 having openings 6 and 7 for communication from the tubes 4 and 5 with a chamber 8 formed by a forwardly extending peripheral flange 9.

Seated upon the front edge of the peripheral flange 9 is an inner closure plate 10 preferably having a recess 11 adapted to receive the edge portion of the peripheral flange 9 with packing interposed to form a liquid tight joint. The inner plate 10 is provided with a pair of openings 12 and 13 through which pass a pair of inner tubes 14 and 15 having a slidably bearing in the openings. The openings 12 and 13 are positioned to support the inner tubes in spaced relation to the outer tubes 4 and 5.

An outer plate 16 is supported on the

inner tubes 14 and 15, and is provided with openings 17 and 18 through which pass the ends of the inner tubes.

The inner plate 10 and the outer plate 16 are preferably spaced one from the other, and are provided with recesses 19, 20, 21 and 22 in their proximate faces in the marginal portions of the respective plates about the openings through which pass the inner tubes 14 and 15. Each of these recesses is adapted to receive resilient packing, and also the rings 23 and 24 loosely positioned about each of the inner tubes. The rings 23 and 24 operate to compress the resilient material in the recesses into liquid-tight contact with the inner tubes 14 and 15 when the outer plate 16 is forced inwardly toward the inner plate 10.

Each of the rings 23 and 24 is constructed with an annular recess 25 formed in its inner surface (see Fig. 5) from which one or more outlets 26 open outwardly through the ring. In the case of any failure in the packing about the tubes 14 and 15, any leakage caused thereby would be intercepted by the recesses 25 and escape through the outlets 26, thus preventing the intermixture of the liquid flowing in the tubes 4 and 5 with that in the tubes 14 and 15. The outward escape of the leakage also gives visible warning of the fact that the packing is leaking, and enables immediate correction.

The outer plate 16 is also provided in its front face with a peripheral recess 27 adapted to receive packing material and within which is supported a flange 28 formed on the inner face of a cover cap 29, the cap 29 being shaped to provide a chamber 30 between it and the outer plate 16 for communication between the inner tubes 14 and 15 extending through the openings in the outer plate 16.

The cap 29 is preferably supported by a pair of lugs 31 pivotally supported on a lever 32, which latter is pivoted on a swinging support 33 hinged on the base 1 as indicated at 34. The free end of the lever 32 is preferably slotted to receive the swinging bolt 35 oppositely hinged on the base 1 and carrying a thumb nut 36 bearing outwardly upon the lever 32 and clamping the separable parts of the head structure in assembled relation.

In operation, the fluid passing between the inner and outer tubes 14 and 4 of the upper of the tier of tubes, as illustrated in Fig. 3, flows through the chamber 8 and into the

space between the outer and inner tubes of the lower pair. The liquid flowing through the upper tube 14, of the inner tubes illustrated in Fig. 3, passes through the chamber 30, formed by the cap, and into the lower of the inner tubes. With the parts of the head structure assembled as described, it will be seen that there is no possibility of intermixing the fluid flowing in the outer tubes with 10 that of the fluid flowing in the inner tubes.

To disassemble the head structure for cleaning, releasing the thumb nut 36 and swinging away the lever 32 with its supported cap 29, permits the ready removal of 15 the inner and outer plates 10 and 16, after which the inner tubes may be withdrawn, and all surfaces of both tubes and head structure with which the fluid is in contact are readily accessible for cleaning and sterilization. 20

I claim as my invention:

1. A device of the class described, comprising a base having a pair of flanged openings adapted to receive the ends of a pair of 25 outer tubes in sealed relation to said base and having an opposite peripheral flange forming a chamber in communication with said openings, an inner plate abutting said latter flange and forming a closure for said 30 chamber, said inner plate having a pair of openings adapted to receive a pair of inner tubes in slidable relation thereto, an outer plate having a pair of openings adapted to receive said pair of inner tubes, recesses in 35 the proximate faces of each of said plates about said inner tube openings adapted to receive a compressible material, a ring positioned in each pair of said recesses between said plates, a cap abutting said outer plate 40 and forming a chamber communicating with each of said inner tube openings therein, and means for securing said base, plates, rings and cap in abutting relation.

2. A device of the class described, comprising a base having a chamber and having a pair of openings communicating with said chamber adapted to receive a pair of outer tubes in sealed relation thereto, an inner plate abutting said base and forming a closure of said chamber, said inner plate having a pair of openings adapted to slidably receive a pair of inner tubes, an outer plate adapted to slidably receive said inner tubes, means between said plates for compressing 50 resilient material about said inner tubes, a cap abutting said outer plate and forming a chamber communicating with said inner tube openings, and means for securing said base, plates and cap in abutting relation.

3. A device of the class described, comprising a base having a chamber and having a pair of openings communicating with said

chamber adapted to receive a pair of outer tubes in sealed relation thereto, an inner plate abutting said base and forming a closure of said chamber, said inner plate having a pair of openings adapted to slidably receive a pair of inner tubes, an outer plate adapted to slidably receive said inner tubes, means between said plates for compressing 65 resilient material about said inner tubes, a cap abutting said outer plate and forming a chamber communicating with said inner tube openings, a lever hinged on said base and pivotally supporting said cap, a member 70 hinged oppositely on said base and having clamping means bearing upon said lever.

4. In a device of the class described, a pair of plates having oppositely disposed openings adapted to receive a tube, recesses in the proximate faces of said plates formed marginally about said openings and adapted to receive resilient material, and a ring disposed in said recesses adapted to compress 75 said resilient material upon said tube with 80 the clamping together of said plates.

5. In a device of the class described, a pair of plates having oppositely disposed openings adapted to receive a tube, recesses in the proximate faces of said plates formed marginally about said openings and adapted to receive resilient material, and a ring disposed in said recesses adapted to compress 85 said resilient material upon said tube with the clamping together of said plates, said ring having a recess in its inner surface 90 adapted to intercept liquid passing between said tube and said resilient material, and having an outlet from said recess for the discharge of the intercepted liquid therefrom. 95

6. A device of the class described, comprising a base having a chamber and having a pair of openings communicating with said chamber adapted to receive a pair of outer tubes in sealed relation thereto, an inner plate abutting said base and forming a closure for said chamber, said inner plate having a pair of openings adapted to slidably receive a pair of inner tubes, an outer plate adapted to slidably receive said inner tubes, a ring between said plates for compressing 100 resilient material about said inner tubes, said ring having a recess in its inner surface adapted to intercept liquid passing along 105 said tube, said recess having an outlet opening therefrom, a cap abutting said outer plate and forming a chamber communicating 110 with said inner tube openings, and means for securing said base, plates and cap in abutting relation.

In witness whereof I hereunto attach my signature.

GRANDON D. GATES.
